United States Patent Office

Des. 186,858
Patented Dec. 15, 1959

186,858

LOCK NUT

Kenneth Reiner, Los Angeles, Calif.

Application November 14, 1955, Serial No. 38,876

Term of patent 14 years

(Cl. D54—9)

FIG. 1.

FIG. 2.

FIG. 3.

FIG. 4.

Fig. 1 is a top plan view of a lock nut showing my new design.

Fig. 2 is a bottom plan view.

Fig. 3 is a section taken along the line 3—3 of Fig. 1.

Fig. 4 is a side elevation taken from the right side of Fig. 1.

I claim:

The ornamental design for a lock nut, substantially as shown.
